UNITED STATES PATENT OFFICE

2,132,943

AUTOMATICALLY IGNITED AND EXTINGUISHED HOT WATER SHAVING BRUSH

William G. Frazier, Philadelphia, Pa.

Application May 4, 1937, Serial No. 140,588

9 Claims. (CL. 132—80)

In my prior patents, 1,813,615 and 1,813,616, dated July 7, 1931, I have described and broadly claimed a novel shaving brush which enables one to heat the water passing to the bristles.

5 In my present invention, I have devised novel means to effect the automatic ignition of the fuel, and the automatic extinguishing of the flame when the water has been heated to a predetermined temperature.

10 Further objects of the invention are to simplify the construction so that the shaving brush can be economically manufactured; to construct and coordinate the parts so that there will not be a fire hazard and the construction will be 15 fool-proof in use; and to provide for the housing of the igniter unit to prevent accidents when the fuel is being poured into the fuel chamber.

With the above and other objects in view as will hereinafter clearly appear, my invention 20 comprehends a novel automatically ignited and extinguished hot water shaving brush.

Other novel features of construction and advantage will hereinafter appear in the detailed description and the appended claims.

25 For the purpose of illustrating the invention, I have shown in the accompanying drawing a typical embodiment of it, which in practice, will give satisfactory and reliable results. It is, however, to be understood that the various instrumentalities of which my invention consists can be 30 variously arranged and organized, and my invention is not limited to the exact arrangement and organization of these instrumentalities as herein set forth.

35 Figure 1 is a side elevation partly broken away of an automatically ignited and extinguished hot water shaving brush, embodying my invention.

Figure 2 is a side elevation, partly broken away 40 showing the brush in burning position.

Figure 3 is a sectional elevation of the parts in closed position.

Figure 4 is a transverse section of the water 45 tank on line 4—4 of Figure 1 to illustrate more clearly the thermostat.

Figure 5 is a side elevation of a shaving brush having a modified contour.

Figure 6 is a top plan view of the container.

50 Figure 7 is a sectional elevation of a portion of the mechanism with the parts in open or burning position.

Figure 8 is a transverse section of the sleeve of 55 the water tank, looking upwardly to show the sealing means.

Similar numerals indicate corresponding parts. Referring to the drawing:

1 designates a cup shaped container, closed at its bottom and open at its top and having within it an annulus of absorbent or wick material 2. 3 is an open ended tube secured in any desired manner within the container 1, for example by spot welding at the bottom, and this tube forms a housing for an igniting unit 4 of well known construction and purchasable in the open market. Beneath the unit is a spring 5 having its lower end preferably fixed, and this spring tends to move the igniting unit upwardly. The upper end of the igniting unit has fixed to it a novel flanged cover 6 closing the upper end of the tube 3 when the parts are in closed position. A rod 7 fixed to the cover projects upwardly to contact with the concave bottom 8 of a water tank 9. To prevent condensation in the tube 3 it is provided with an atmospheric port 10 opening through the bottom of a lower cap 11 which receives the container 1. The outer periphery of this cap is preferably knurled and at its upper portion it is of reduced diameter and threaded as at 12.

25 The tank has depending from it a sleeve 13 in telescopic relationship with the container 1 and provided with rows of air ports 14, 15 and 16, the ports in the different rows being preferably in staggered relation, and the two upper rows 30 being smaller in diameter than the lowermost row. The bottom of the tank 9 is grooved near its outer periphery as at 17 to receive a sealing gasket 18 of asbestos or other suitable material with which the upper end of the container 1 will 35 contact when the parts are in closed position as will be understood from Figure 3. The water tank 9 converges upwardly and terminates in a threaded enlargement 19 to receive the threaded apertured base 20 in which the bristles 21 are 40 securely set. A valve 22 having a handle 23 may be employed if desired to control the communication between the tank 9 and the bristles 21.

45 The tank 9 is preferably provided with an annular recess 24 to receive the thermostatic members 25, any desired number of which may be employed, three of such members being shown. Each of these members is of bi-metallic thermostatic material having one end fixed to the wall 50 of the tank and their outer ends free to move inwardly when the temperature of the water in the tank 9 has reached a predetermined degree to release their pressure against the inner wall of an outer sleeve 26 and permit it to drop suf- 55

ficiently to close the air ports 16, 15 and 14 and thus extinguish the flame. The lower end of the sleeve 26 is internally threaded to cooperate with the threads 12 of the cap 11. The inner wall at the lower end of the sleeve 26 is grooved to receive a split ring 27, which may be of thermostatic material, and which serves to prevent the accidental removal of the sleeve 26. The upper end of the sleeve 26 converges towards the top so that when in its lowermost position it will be sealed with the wall of the tank.

The embodiment shown in Figure 5 is similar to that shown in the other figures except that the sleeve 26 is inwardly curved to provide a better 15 grasping portion for the user.

The operation will now be apparent to those skilled in this art and is as follows:

The base 20 is unscrewed and the water tank 9 filled to a desired amount with water. Alcohol 20 or other ignitable fuel is placed in the container 1 to saturate the wick 2 and the sleeves 13 and 26 are moved into the position seen in Figure 3 with the outer sleeve 26 screwed to the cap 11. The shaving brush is now ready for repeated 25 operations. The user unscrews the sleeve 26 and the spring 5 raises the igniting unit 4 and the inner sleeve 13 so that the openings 14, 15 and 16 are uncovered, and the sleeve 26 is raised into the position seen in Figure 2. The air entering the 30 ports causes the igniting unit to glow and the alcohol is ignited, thus heating the water in the tank 9. The outer sleeve 26 is retained in its raised position by the thermostatic members 25 contacting with its inner face until the water 35 reaches a predetermined temperature, whereupon the members 25 will move inwardly to release the outer sleeve which will drop sufficiently to close the ports 14, 15 and 16. This causes the burner to be extinguished as the flow of air to 40 the burner is cut off. The user then presses the outer sleeve downwardly against the pressure of the spring 5 and screws it to the cap 11. The operator can now use the shaving brush in the conventional manner, the hot water passing to 45 the bristles. If the valve 22 is employed, such valve is of course opened.

When the outer sleeve 26 is raised, the stop 27 engaging the thermostat will prevent the sleeve 26 being detached from the sleeve 13. 50 When the water in the tank is warm, the stop 27 will slide over the thermostat.

The atmospheric vent 10 prevents condensation in the tube 3, so that the igniting unit 4 will ignite the fuel as soon as the sleeve 13 raises sufficiently 55 to uncover the air ports. The upper row of ports 15 and 16 prevent the flame from the burner flaring out through such ports.

The bottom cap 11 has openings 28 to the atmosphere. If desired, the part 10 may be controlled by a valve 29 of any desired character. As shown, a rotary ported valve is mounted on the bottom cap so that the valve may be turned to open or close the port 10 as may be desired.

Having thus described my invention, what I claim as new and desire to secure by Letters Patent is:—

1. In a shaving brush, a sectional casing, one section of which contains fuel and an igniting unit, and another section of which forms a water tank and carries a fountain brush, means to effect relative movement of said sections to admit air to the igniting unit, and means controlled by the temperature of water in the water tank to automatically prevent admission of air to the igniter 75

unit when the temperature of the water reaches a predetermined degree.

2. In a shaving brush, a sectional casing, one section of which contains fuel and an igniting unit, and another section of which forms a water tank and carries a fountain brush, means to automatically effect relative movement of said sections to admit air to the igniting unit, and means controlled by the temperature of water in the water tank to automatically prevent admission of air to the igniter unit when the temperature of the water reaches a predetermined degree. 10

3. In a shaving brush, a container open at its top, a fuel absorbing wick in the container, an igniter in the container, a water tank, a brush receiving water from the tank, a sleeve connected with the tank in telescoping relationship with the container and having air ports communicating with the container when the sleeve is raised, an outer sleeve slidable on said tank sleeve, and thermostatic means to retain the outer sleeve in position to open the ports, and to release the outer sleeve to permit it to drop to cover said ports when the water in the tank is heated to a predetermined degree. 15

4. In a shaving brush, a container open at its top, a fuel absorbing wick in the container, an igniter in the container, a water tank, a brush receiving water from the tank, a sleeve connected with the tank in telescoping relationship 20 with the container and having air ports communicating with the container when the sleeve is raised, an outer sleeve slidable on said tank sleeve, a spring tending to relatively move said container and tank sleeve to cause the ports to 25 have atmospheric communication with said container, and thermostatic means to retain the outer sleeve in position to open the ports, and to release the outer sleeve to permit it to drop to cover said ports when the water in the tank 30 is heated to a predetermined degree. 35

5. In a shaving brush, a container open at its top, a fuel absorbing wick in the container, an igniter in the container, a water tank, a brush receiving water from the tank, a sleeve connected with the tank in telescoping relationship with the container and having air ports communicating with the container when the sleeve is raised, an outer sleeve slidable on said tank sleeve, a spring tending to relatively move said 40 container and tank sleeve to cause the ports to have atmospheric communication with said container, and thermostatic means to retain the outer sleeve in position to open the ports, and to release the outer sleeve to permit it to drop 45 to cover said ports when the water in the tank 50 is heated to a predetermined degree, and said outer sleeve and casing having means to secure 55 them together.

6. In a shaving brush, a container having an open top, a wick in the container, a tube fixed to the container and open at its top, a spring in the tube, an igniter above the spring, a cover to close the top of the tube, and a closure for the upper end of the container. 60

7. In a shaving brush, a container having an open top, a wick in the container, a tube fixed to the container and open at its top, a spring in the tube, an igniter above the spring, a cover to close the top of the tube, a closure for the upper end of the container, and means actuated by the spring to move the closure into open position. 65

8. In a shaving brush, a container having an open top, a wick in the container, a tube fixed 70 to the container and open at its top, a spring in the tube, an igniter above the spring, a cover to close the top of the tube, a closure for the upper end of the container, and means actuated by the spring to move the closure into open position. 75

to the container and open at its top, a spring in the tube, an igniter above the spring, a cover to close the top of the tube, said tube being in ported communication with the atmosphere to prevent condensation in the tube in proximity to the igniter, and a closure for the upper end of the container.

5 9. In a shaving brush, a container having an

open top, a wick in the container, a tube fixed to the container and open at its top, a spring in the tube, an igniter above the spring, a cover to close the top of the tube, said tube being in valved communication with the atmosphere and 5 a closure for the upper end of the container.
